DESIGN FOR A VENETIAN BLIND TILTING DEVICE

Edwin Anderson, Los Angeles, Calif., assignor to
Anderson Die Casting and Engineering Cor-
poration, Los Angeles, Calif., a corporation of
California

Application May 11, 1937, Serial No. 69,301

Term of patent 14 years

To all whom it may concern:

Be it known that I, Edwin Anderson, a citizen
of the United States, residing at Los Angeles, in
the county of Los Angeles and State of California,
have invented a new, original, and ornamental
Design for a Venetian Blind Tilting Device, of
which the following is a specification, reference
being had to the accompanying drawing, forming
part thereof.

Figure 1 is a perspective view of a Venetian

blind tilting device illustrating my new design;
Figure 2 is a top plan view; and
Figure 3 is a side elevational view thereof.

The design is characterized particularly by the
symmetrical form of the lower portion of the tilt
having a rectangular opening therein.

I claim:

The ornamental design for a Venetian blind
tilting device, as shown and described.

EDWIN ANDERSON.
